P. J. EUBANKS ET AL

COMPENSATING DEVICE FOR CARBURETORS

Original Filed July 14, 1920

UNITED STATES PATENT OFFICE.

PERRY J. EUBANKS AND CHARLES W. RUSH, OF CLEVELAND, OHIO.

COMPENSATING DEVICE FOR CARBURETORS.

Application filed July 14, 1920, Serial No. 396,161. Renewed January 2, 1925.

To all whom it may concern:

Be it known that we, PERRY J. EUBANKS and CHARLES W. RUSH, citizens of the United States, residents of Cleveland, county of Cuyahoga, and State of Ohio, have invented new and useful Improvements in Compensating Devices for Carburetors, of which the following is a specification, the principle of the invention being herein explained, and the best mode in which we have contemplated applying that principle, so as to distinguish it from other inventions.

Our invention relates to carburetors, and particularly to compensating devices whereby proper proportions of fuel and air may be fed to a motor to enable the same to function properly, irrespective of temperature conditions, without limiting the amount of air necessary to operate at maximum efficiency.

The annexed drawing and the following description set forth in detail certain means embodying our invention, the disclosed means, however, constituting but one of the various mechanical forms in which the principle of the invention may be applied.

In said annexed drawing:

Figure 1 represents a vertical longitudinal section of the air inlet pipe and a carburetor involving the elements of our improved compensating device, showing, in full lines, an intermediate position, of an air inlet valve and some connected parts, resulting from the pressure difference between a chambered member on the inside of the valve controlling the air inlet and the normal outside atmospheric pressure, incident to a given motor speed; and, in dotted lines, extreme positions of said valve and parts under other motor speeds. This view shows an elevation of fragmentary parts of a carburetor proper.

Figure 2 is a broken plan view of a carburetor portion including our improved compensating device;

Figures 3 and 4 are sections similar to Figure 1, but showing respectively the starting and full open positions of the compensating device; and

Figure 5 is a broken section and elevation of the valve and some connected parts.

Referring to the annexed drawing, wherein the same ordinals refer to like parts in the different figures, 1 represents an air conduit of a carburetor 2 having a flanged pipe 3 leading to the manifold, not shown. Secured by means of screws 4' and flange 4" to one

end of a chambered member 5, is a pipe 4, which chambered member 5, in turn, is secured at its other end by means of screws 6' and flange 6" to a pipe 6 communicating with the atmosphere or communicating with an air heating device, not shown. The pipes 4 and 6 are formed respectively with spiders 7 and 9 having central hubs 8 and 10 respectively forming bearing bushings for a pair of reciprocable plungers 11 and 12, respectively. The plungers 11 and 12 are secured together in any suitable manner, or may, if desired, be a single member, and a valve is mounted thereon to control the inner open end of the pipe 6. In the means shown in the accompanying drawing, which are but an exemplification of the method of securing the plungers 11 and 12 together and of the mounting of the valve, the plunger 12, at one end, is formed with a threaded extension 13 adapted to be tapped into an enlarged end portion 18 of the plunger 11. The valve is illustrated by the ordinal 15, and is formed with a central recess 16 through which the threaded member 13 passes, the valve thus being tightly mounted upon the plunger 11—12, as plainly shown in Figure 5. The valve 15 is adapted to seat over the inner opening 17 of the pipe 6. This valve 15 is normally held to its seat, as hereinafter fully described, by means of a coil spring 25 in combination with a pin 21 and some related elements. In the form of device shown, this coil spring 25 is mounted upon the plunger portion 18, and is disposed between the valve 15 and one face of a sleeve 20, which is also mounted upon the plunger portion 18. This plunger portion 18 is formed with an elongated slot 19 through which passes a pin 21 secured in the sleeve 20 and extended laterally of said sleeve on both sides. The pin 21 is longitudinally movable in the elongated slot 19 relatively to the plunger 11—12. A hub 23 of a yoke-shaped member 22 is secured to a shaft 24, the respective arms 22' of the yoke enclosing the sleeve 20, and each being formed with two fingers 22" spaced so as to provide recesses 22' into which the two ends of the pin 21 extend. The shaft 24 is actuated from the dash or any suitable operating position upon the machine by any desired connecting means 14.

The device which we have just described, and which is shown in the accompanying drawings, is intended to serve as a very ef-

fective air furnishing means for the carburetor 2 both during the early stages of operation, when the motor is being heated up, and during the later stages, when the normal operation takes place. It is well known that, due to the increased weight of cold air and the increased viscosity of the fuel, the motor, while being heated, can not obtain the proper amount of fuel which, in proportion to the air, should be maintained at all times for normal running. Therefore, when starting with a cold motor, our device is positioned as shown in Figure 3, in which position the pin 21 engages the forward end of the slot 19 in the plunger 12 whereby the valve 15 is locked solidly against the seat 17 and thus the suction or pressure head is directed entirely against the source of fuel supply, thereby furnishing a charge of pure fuel to the motor. Immediately after the first explosion of the motor, the device is moved to a position where it is possible for some air to be furnished by the valve 15, such position being termed by us an "intermediate position," and an exemplification of this position is shown in Figure 1. In this position the pin 21 is in an intermediate portion of the slot 19 whereby the plunger 12 is movable with respect to the sleeve 20 against the action of the spring 25 and the valve 15 has a range of movement, dependent upon the suction, between the dotted line positions of the valve shown in Figure 1. A position of the valve for a given motor speed is indicated by the full line position in said figure. At other motor speeds, the valve 15 would be disposed at some position intermediate the two extremes shown by dotted lines. This adjustment of the device from the locked position shown in Figure 3 to the intermediate position shown in Figure 1, is effected by the operation of the shaft 24, which, through the yoke arms 22' and pin 21, moves the sleeve 20 relatively to the plunger 18, relaxing the tension of the spring 25. It is evident that, dependent upon the intermediate position to which the device is moved, the same amount of suction or the same motor speed will effect a differential in the amount of opening movement produced by the valve 15. Also, dependent likewise upon the intermediate position to which the device is set, different motor speeds will effect a differential in the comparative amounts of opening movements produced in the valve 15. When the motor has been properly warmed up, the device is moved to the position shown in Figure 4, in which position the pin 21 is in engagement with the rear end of the slot 19 in the plunger 12 whereby all tension of the spring 25 against the valve 15 is eliminated and the valve 15, plunger 12, sleeve 20 and interposed spring 25 have been moved bodily as a unit to space the valve 15 sufficiently from its seat 17 to

provide a passage past the valve of cross sectional area equal to or greater than the cross sectional area of the passage from the passage 6 into the chamber 5, so that then the carburetor is permitted to acquire a supply of air for all operative requirements, without the functioning of our improved compensating device. 70

During the warming-up process, illustrated by the position shown in Figure 1, whenever the motor slows down the valve 15 will tend to go to the seat 17, which will create a higher suction upon the fuel and thus add the desired additional fuel. Without this compensation, at slow motor speeds, 80 the gasoline openings are comparatively too small, during the warming-up period of the motor, unless some added suction is super-induced or the amount of fuel increased in some manner. Thus the motor is not sufficiently fed with fuel. Our device allows for the necessary added suction upon the fuel at these slow motor speeds, and thus in this manner furnishes the desired additional comparative amount of fuel, without 88 limiting the amount of air that is necessary for successful operation at any motor speed. 90

Our compensating device allows for the production of a differential in the opening movement of a carburetor air inlet valve 95 produced by the same amount of suction and has a range of movement from a position in which the valve positively is held in a closed position to a position where the device is absolutely inoperative, in so far as any effect 100 upon the opening movement of the valve is concerned. 100

What we claim is:

1. In compensating devices for carburetors, the combination with a carburetor 105 formed with an air inlet; of a valve for said inlet; and means operable to positively hold said valve in closed position; yieldingly hold said valve against opening movement and positively hold said valve in full open position.

2. In compensating devices for carburetors, the combination with a carburetor formed with an air inlet; of a valve for said inlet; a plunger to which said valve is secured; a sleeve slidably mounted upon said plunger; a spring interposed between said sleeve and valve; an actuating lever connected to said sleeve; and means interposed between said sleeve and plunger for limiting the movement of said sleeve with respect to the plunger in both directions whereby said valve may be positively held by said lever in closed and full open positions. 115

3. In compensating devices for carburetors, the combination with a carburetor formed with an air inlet; of a valve for said inlet; an actuating lever for said valve; and means interposed between said lever and valve adapted to provide a yielding connection. 125

tion between said lever and valve when said lever is in intermediate positions and a direct connection between said lever and valve when said lever approaches its limit of movement in either direction.

4. In compensating devices for carburetors, the combination with a carburetor formed with an air inlet; of a valve for said inlet; a shiftable controlling member

for said valve; and a spring interposed between said valve and controlling member for yieldingly resisting opening movement of said valve, said controlling member being directly engageable with said valve to shift said valve to inoperative position.

Signed by us this 30th day of June, 1920.

PERRY J. EUBANKS.

CHARLES W. RUSH.
